NIGHT LIGHT

Lawrence P. Mellyn, Gloucester, R.I., assignor to General Electric Company, a corporation of New York

Filed Mar. 4, 1965, Ser. No. 84,093

Term of patent 14 years

(Cl. D48—20)

FIG. 1.

FIG. 2.

FIG. 3.

FIG. 4.

FIG. 5.

FIG. 6.

FIG. 7.

FIG. 8.

FIG. 1 is a back perspective view of a night light embodying my new design;

FIG. 2 is a front perspective view thereof;

FIG. 3 is a front perspective view thereof as shown in separated condition;

FIG. 4 is a back elevational view thereof;

FIG. 5 is a side elevational view thereof;

FIG. 6 is a front elevational view thereof;

FIG. 7 is a bottom plan view thereof; and

FIG. 8 is a top plan view thereof.

The dominant features of my design reside in the portions shown in full lines.

I claim:

The ornamental design for a night light, as shown and described.
